US00D835470S

(12) **United States Design Patent** (10) **Patent No.:** **US D835,470 S**
(45) **Date of Patent:** **** Dec. 11, 2018**

(54) **CONTAINER**

(71) Applicant: **YETI Coolers, LLC**, Austin, TX (US)

(72) Inventors: **Roy Joseph Seiders**, Austin, TX (US);
James William Sonntag, Austin, TX (US);
Christopher Mall Keller, Austin, TX (US);
Steve Charles Nichols, Austin, TX (US);
Martin Patrick Vespo, Austin, TX (US)

(73) Assignee: **YETI Coolers, LLC**, Austin, TX (US)

(**) Term: **15 Years**

(21) Appl. No.: **29/610,438**

(22) Filed: **Jul. 12, 2017**

(51) LOC (11) Cl. **07-01**

(52) U.S. Cl. **D7/605**

(58) **Field of Classification Search**

USPC D7/605–608, 629, 630; D3/272–274
CPC .. A45C 11/20; A45C 5/14; A45C 5/03; A45C 9/00; A47B 77/08; A47G 19/2288; B26B 3/003; F25B 19/00; F25D 3/08; F25D 3/12; F25D 3/02; F25D 3/14; F25D 2331/804; F25D 2400/08; F25D 31/005; B65D 81/3858; B65D 81/3823; B65D 81/3813; B65D 81/3888; B65D 81/3816

(57) **CLAIM**

The ornamental design for a container, as shown and described.

DESCRIPTION

FIG. 1 is a top, front, right perspective view of a container showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing the remainder of the container represent unclaimed subject matter and form no part of the claimed design.

1 Claim, 7 Drawing Sheets
